UNITED STATES PATENT OFFICE.

THEODORE REGENSTEINER, OF CHICAGO, ILLINOIS.

PATTERN-EXHIBITOR.

1,129,811.

Specification of Letters Patent. Patented Feb. 23, 1915.

Application filed September 22, 1913. Serial No. 791,236.

To all whom it may concern:

Be it known that I, THEODORE REGENSTEINER, a citizen of the United States, residing at Chicago, in the county of Cook and State of Illinois, have invented certain new and useful Improvements in Pattern-Exhibitors, of which the following is a specification.

This invention relates to pattern exhibitors, the arrangement of the constituent parts thereof, and the method by which reproductions of the dummy are made.

In the present invention I have devised a dummy device for displaying patterns in the construction of which a great deal of the labor and expense usually attending such work is eliminated. I also have secured a more perfect and definite reproduction of the goods displayed in the pattern exhibitors of my invention, so that the appearance of the goods as actually worn is more clearly and satisfactorily exhibited.

The invention, as will be seen from a study of the specification and drawings, is also concerned with numerous other features of novelty which will hereinafter appear.

In making reproductions of fashion-plates and other designs embodying fabrics and textile goods for catalogue work, posters or other display purposes, it is customary to employ skilled artists to prepare a dummy picture exhibiting clothed figures in artistic postures, and to manually copy thereon, as closely as possible, the appearance of the texture and weave of the clothes exhibited by the figures. Obviously this involves the most painstaking labor of skilled artists, and in most cases the appearance of the texture and weave of the goods so manually reproduced is of necessity imperfectly represented. From fashion-plate dummies so laboriously prepared, photographic reproductions are made in one or more colors as desired, the reproduction, of course, embodying whatever defects may exist in the dummy as originally prepared. In my invention, I aim to eliminate a large part of the painstaking work, for which skilled artists are employed, by the preparation of a novel dummy fashion-plate, in which the texture and weave of the cloth itself, is displayed for the purpose of being photographed, or otherwise reproduced.

In the drawings: Figure 1 is a view of a sheet of transparent material with a human figure outlined by a background rendered

opaque through the use of suitable pigments; Fig. 2 is a view of the rear side of said transparent material, showing a number of sections of cloth arranged over the transparent portion thereof; Fig. 3 is a front view similar to Fig. 1, showing the appearance of the textile goods as displayed through the transparent window-like portion of the material; Fig. 4 is a similar view to Fig. 3, showing additional possibilities in the display of two or more different fabrics; and Fig. 5 is a sectional view taken through the dummy.

In the embodiment of my invention I employ a sheet of transparent material, such as celluloid, on the rear side of which are painted the outlines 6 of a human figure, surrounding which is a background 7 rendered opaque by suitable pigments, except for that portion inclosed within the marginal lines 6. It is to be understood that the invention has particular reference to the preparation of fashion-plates, so that the portion of the figure left transparent within the marginal lines 6 is only that which would ordinarily be clothed with outer garments made from the fabric to be exhibited. Such portions 8, as the gloves, shoes, collar, face, hat, etc., would be artistically painted in, and be rendered opaque by the application of the pigments, preferably on the rear side.

One or more sections of cloth 8, from which an outer garment is made are secured against the side of the sheet and arranged to be displayed through the transparent portion of the figure, thereby exhibiting in a true manner the texture, weave, and color of the garments as actually worn. Except where such sections meet, it is not necessary that they be cut to any particular shape. As best shown in Figs. 2 and 3, these sections, for purposes of illustration, are represented as comprising lapel portions 10, two sleeve portions 11, and coat and trousers portions 12, the number of such sections depending entirely upon the postures in which the figures are represented, and the manner in which they are dressed. The sections of material underlie the transparent portions of the sheet in such a way as to have their edges concealed effectively by the opaque background and marginal lines thereon.

In Fig. 3 the dress goods to be exhibited are shown as formed with a stripe, the sections of material 9 being laid in position in

- such a manner as to correctly represent the direction of the stripe in the dress goods as worn. Where the edges of the sections adjoining, shade lines representing creases or 5 shadows may be painted over the transparent portion of the sheet in an artistic manner so as to conceal effectively the meeting edges of the cloth sections. After the sections of cloth have been arranged correctly 10 about the transparent portion of the sheet, a filling 13 of any suitable material may be used, if desired, against which a backing 14 may be secured in order to protect the assembled parts of the dummy fashion-plate.
- 15 In actual practice it is customary to arrange several figures in one dummy, which are photographed together, and which constitute a single fashion-plate.

It is to be noted that in some instances the 20 pattern in the weave of the dress goods may be of so large a size as to be wholly disproportionate to the size of the figure with which it is exhibited. In order to more correctly maintain the proportions between the 25 figure and the fabric pattern, it may be found desirable to photograph and reproduce in colors on a small scale a piece of dress goods, which colored photograph may then be used in lieu of the cloth itself to be 30 exhibited through the transparent portion of the sheet. This practice may also be found desirable in cases where the dress goods is so thick as to bulge forward the transparent portion of the sheet when placed 35 in position adjacent thereto, or when the appearance of the texture of the goods is altered by contact with the transparent surface.

From the foregoing description, it will be 40 observed that the completed dummy fashion-plate is one which supplements the work of an artist in outlining the figures in a pleasing and artistic manner by clothing the outlined figures in the actual material which it 45 is intended to reproduce for display and advertising purposes. In thus preparing the dummy, it is possible to faithfully repro-

duce the color, texture, and pattern of the goods displayed, and to exhibit the same in a manner which will most efficiently guide 50 the purchaser in a selection of the desired material. The employment of a transparent sheet of material outlined and rendered opaque as described, is preferable to the use of an opaque sheet having portions bodily 55 cut therefrom, in that it affords a more faithful representation of the clothed human figure, and in that it permits creases, pockets, and other characteristic features of a life-like figure to be painted or drawn upon those 60 portions of the figure which overlie the fabric displayed therethrough. In the photographic reproductions made from a dummy thus prepared, the built-up character of the dummy cannot be detected, and every portion of a clothed human figure is portrayed 65 with the utmost fidelity and artistic effect.

Although the invention has been shown as employed for the purpose of exhibiting fabrics used in the making of men's suits and 70 overcoats, it is obvious that it could be similarly employed in the displaying of neck ties or other articles of wearing apparel as actually worn on the person.

I claim:

As a new article of manufacture, a fashion plate dummy embodying a sheet having a transparent portion therein representing the silhouette of a clothed human figure, and a plurality of sections of fabrics or fac-similes 80 thereof arranged to appear through said transparent portion, each said section of fabric being configured to conform with the adjacent sections, arranged to represent a definite portion of the clothed figure, and 85 having its weave disposed in substantially the same direction as would appear in a faithful representation of the corresponding portion of a clothed figure, substantially as described.

THEODORE REGENSTEINER.
